UNITED STATES PATENT OFFICE.

JOHN JAMES HEYWOOD, OF FALL RIVER, MASSACHUSETTS, ASSIGNOR OF ONE-HALF TO FRANCIS SEYMOUR, OF PATERSON, NEW JERSEY.

SUPPORT FOR SPINNING-SPINDLES.

SPECIFICATION forming part of Letters Patent No. 410,279, dated September 3, 1889.

Application filed November 12, 1886. Serial No. 218,703. (No model.)

To all whom it may concern:

Be it known that I, JOHN JAMES HEYWOOD, of Fall River, in the county of Bristol and State of Massachusetts, have invented a new and useful Improvement in Supports for Spinning-Spindles; and I do hereby declare the following specification, taken in connection with the accompanying drawings, forming a part of the same, to be a description thereof.

10 The invention consists in mounting the spindle within a step or bearing, which bearing is mounted and supported so as to be revoluble within a hollow case or bearing, as hereinafter described and claimed, whereby 15 the friction caused by the revolution of the spindle will be distributed so that the spindle can be run at a higher speed.

The invention also consists in certain features of construction and arrangement described and claimed.

In the accompanying drawings, Figure 1 is a view representing the end of the driving-cylinder and a spindle arranged in accordance with my invention, the spindle and its connections being shown in central vertical section. Fig. 2 is a plan view of two spindles and a portion of the driving-cylinder, two systems of banding being represented. Fig. 3 is a plan view of two spindles and a portion 30 of the cylinder, showing a modified system of banding. Fig. 4 is central vertical section of a spindle and the parts in which it is mounted, two revoluble steps or bearings being employed.

35 Referring to the drawings, 10 is the step-rail of a spinning-machine, and 12 is a hollow supporting-case mounted therein, closed at its lower end, and having a flange at its upper end, which rests upon the rail, the case being 40 secured to the rail by a set-screw 13.

11 is the driving-cylinder.

Within the case 12 is stepped the revoluble tubular spindle-bearing 14, which is provided with a whirl 15, and preferably with an upwardly-extending sleeve 16. Into the bearing-tube 14 is stepped the pintle 17 of the live-spindle 18, which is furnished with a whirl 19, and the upper portion of said bearing-tube acts as a bolster-bearing for the spindle.

50 In banding the spindle a single band such

as is shown in the upper part of Fig. 2 may be employed, which band passes about the whirl 19 and about the cylinder 11, or, as shown in the lower portion of Fig. 2, the band may be carried about the whirl 19, then to 55 and about the cylinder 11, then back and about the whirl 15, then about the cylinder again and the ends of the band joined; or, if deemed advisable, instead of driving a single spindle by a single band, as shown in Fig. 2, 60 one band may be used to drive two spindles, as shown in Fig. 3, by carrying the band from the cylinder about one of the whirls 15, to and about the other whirl 15, back and about the whirl 19 on the first spindle, then about the 65 whirl 19 on the second spindle, thence about the cylinder to connect with the other end of the band. When the spindle and the revoluble step 14 are banded, as shown in the lower portion of Fig. 2 and in Fig. 3, the number of 70 revolutions of the step 14 relatively to the spindle will depend upon the size of their respective whirls. If the whirl 15 be twice the diameter of the whirl 19, the bearing 14 will revolve about half the number of times that 75 the spindle revolves. So, if the spindle be revolved twelve thousand revolutions per minute, the bearing 14 will turn six thousand revolutions in the same time, and the friction on the spindle will be only equal to that 80 caused by six thousand revolutions per minute in a stationary bearing.

Although I prefer to employ but one revoluble step or bearing, I may under certain circumstances use two of such bearings, one 85 being supported so as to revolve upon the other, thus still more distributing the friction. The arrangement of two revoluble bearings is shown in Fig. 4, where the spindle-bearing 14 is stepped within a revoluble bearing 20, 90 which is furnished with a whirl 21, and the latter bearing is stepped within the supporting-case 12. With this construction the friction caused by the revolution of the spindle will be distributed upon the two revoluble bearings 14 and 20, thus providing for an exceedingly high rate of speed in the spindle.

What I claim, and desire to secure by Letters Patent, is—

1. The combination, with a hollow support-

ing-case, of a spindle-bearing provided with a whirl, which bearing is stepped into said case and is capable of revolving therein, as described, and a spindle extending down into 5 and stepped within said bearing and provided with a whirl, substantially as set forth.

2. The combination, with the rail of a spinning-frame, of a hollow supporting-case secured thereto, a bearing having a whirl and 10 stepped into said case, so as to revolve therein, as described, a spindle provided with a whirl and extending down into and stepped within said bearing, a driving-band common to the two whirls, and means, substantially as de- 15 scribed, for driving the band, substantially as set forth.

3. The combination, with the supporting-case 12, of a spindle-bearing 14, stepped into said case and having a whirl 15 and an up- 20 wardly-extending sleeve 16, and the spindle 18, extending down through said sleeve and whirl and stepped at its lower end into said bearing and having a whirl 19, surrounding the sleeve 16, substantially as set forth.

4. The combination, with the hollow sup- 25 porting-case 12, of the bearing 20, stepped therein, the spindle-bearing 14, stepped within the bearing 20, and the spindle 18, having a whirl and extending down into and stepped within the bearing 14, substantially as set 30 forth.

5. The rotating or live spindle and the tube containing bolster and step bearings for the spindle and provided with a whirl whereby the said tube may be rotated, combined with 35 a case or holder for the tube and a step for the tube, substantially as set forth.

6. The spindle, the bearing-tube provided with a whirl, and a step for the tube, combined with means to rotate the said spindle 40 and bearing-tube, substantially as set forth.

JOHN JAMES HEYWOOD.
